UNITED STATES PATENT OFFICE.

NORMAN BLYTHE BRALY, OF BUTTE, MONTANA.

FACTORING DEVICE.

1,354,375.

Specification of Letters Patent. Patented Sept. 28, 1920.

Application filed July 7, 1919. Serial No. 308,969.

To all whom it may concern:

Be it known that I, NORMAN B. BRALY, a citizen of the United States, residing at Butte, in the county of Silver Bow and 5 State of Montana, have invented certain new and useful Improvements in Factoring Devices, of which the following is a specification.

The present invention relates to means or 10 apparatus for securing efficiency records of workmen, and more particularly for determining the individual capacities of men working together or in gangs. It has been found especially useful in connection with 15 mining operations, but is of course not restricted in its scope to the same. The said apparatus, in effect, constitutes part of a system that has proven efficacious and thoroughly successful in actual practice.

20 In the accompanying drawings:—

Figure 1 is a view in elevation of a factoring device and a record card in place therein and in proper relation to easily determine the efficiency of the men employed in certain predetermined operations.

25 Fig. 2 is a cross sectional view through the same.

Fig. 3 is a view similar to Fig. 2, but with the card removed.

30 Fig. 4 is a detail view in elevation of a portion of the factoring device with the card removed.

Fig. 5 is a face view on an enlarged scale of the record card *per se*.

35 Similar reference numerals designate corresponding parts in all the figures of the drawings.

Referring first to the card illustrated in Fig. 5, the same is utilized for recording 40 certain features of mining work when performed by two men, though the card may be modified for the records of any number working together. This card comprises two sections 6 and 7 with a line of perforations

45 8 defining the said sections and affording convenient means for separating them. The card is provided in its left hand margin with openings 9, whereby it or its sections may be placed in binders. The card fur-

50 thermore has on the left hand portion pictorial representations 10 of different operations in mining. The different features of the illustrations have descriptive titles 11 and are also provided with reference char- 55 acters "A," "B," "C," etc., as shown.

The right hand portion of the card or sheet is provided with columns of defined spaces 12 and 13, the latter being preferably shaded as shown, and the different spaces are identified by reference characters corresponding to those applied to the different pictorial representations. Each section is furthermore provided with a ruled line 14 to receive the number by which a workman is identified, the word "Number" preferably preceding said line, as shown. Directly beneath that line is another line 15 adapted to receive the average to be determined by the record made of the workman's actual operations, and this line 15 is preferably preceded as shown by the word "Total." In addition, each section is provided with a line 16 preceded by the word "Place" and adapted to receive a number designating the particular portion of the mine in which the operations are carried out.

In connection with cards of the character above described, there is employed a factoring device shown in Figs. 1-4 inclusive. 80 This device consists of a suitable body plate 17 having pins 18 extending from one side, and provided with terminal knobs 19 by which the plate can be mounted in a rack with others of an analogous character. This 85 body has preferably printed upon it as shown at 20 a title defining the particular work to be determined thereby, and also having a designation, as 21 of the mine in which said work is carried on. Upon one 90 face of the body 17 is placed a sheet of transparent material 22, preferably celluloid, held in place by screws 23 or other fasteners. This sheet 22 is separated from the body 17 by a spacing sheet 24 interposed between the two and cut out to form a card-receiving pocket 25. Upon the sheet is a column of factors 26.

In order to explain the utility of the device, a concrete example will be given, employing the factors shown in connection with the card as illustrated. 1,000 units is taken to represent the perfect score for a week's work of 6 days, or 166.66 units per day. In other words 1,000 units is equivalent to 100%. If 8 hours is taken as the basis of a day's work, the men go to their places of work on company time, which takes about half an hour, and after reaching their working places, half an hour ad-

ditional company time is allowed to make their places safe. Under this method of calculating the men's time, they actually work only 7 hours, or 420 minutes. 420 divided by 166.66 units (a perfect day's work) gives 2.52 minutes work per unit for two men. In other words when two efficient men work together for 2.52 minutes they have accomplished 1 unit of work of the 10 1,000 units, which form a week's work of 6 days. The factors on the celluloid sheet are determined as follows:—Taking, for example, the letter "A" on the record card illustrated, it will be noted that it designates a mine post. It is found that the actual time required to put in a mine post under predetermined conditions is 7.8 minutes, and dividing it by 2.52, the ratio above given, the resulting factor is 3.1. Furthermore, the actual time it takes to put in a cap ("B" on the illustration) is 10.6 minutes. This divided by 2.52 gives a unit of 4.2 for the factor, and thus the list is determined for all the operations illustrated. These 25 factors, as will be noted by reference to Figs. 1 and 4, are placed in a column on the transparent sheet 22, and are so located that when the card 6—7 is placed in the pocket 25, the factors will be over the shaded spaces 13 and aligned with the respective spaces in which the records for the different operations are to be recorded.

All that is necessary therefore to determine the efficiency of a man is to ascertain 35 just what work was done by him and his associates and factor it. Thus, in the present example, two men No. 702 and No. 483 working in Place No. 2858 on May 20, 1919, effected the following operations.

- 40 A put in 4 posts.
- B put in 2 caps.
- C put in 5 girts.
- D put in 8 blocks.
- G hoisted 11 pieces of timber.
- 45 N laid 10 pieces of flooring.

The date of the operation, it will be noted, is stamped on both sections, and the number of the mine boss "18" is also stamped on both sections. If now this card is placed 50 in the pocket 25, the following results can be readily determined:

A	4	4 × 3.1 = 12.4
B	2	2 × 4.2 = 8.4
C	5	5 × 3.2 = 16.0
D	8	8 × 4.0 = 32.0
G	11	11 × 3.2 = 35.2
N	10	10 × 1.0 = 10.0

60 Total 114.0

These two men, therefore, have each secured 114 units out of a possible 166.66 for the day's work, and their efficiency for the day would be 114/166.66, or 68.4%.

65 As a matter of convenience, however, the

efficiency is not determined every day, but only once a week. The coupons or sections of the cards are separated each day and filed together under the man's working number. It will make no difference therefore how 70 men are shifted from place to place, nor the different characters of work they may perform. Their average can readily be ascertained, and they may thus be properly classified. For example, the cards for the man 75 No. 702 for the week may appear as follows:

114			
144			
126			
152			
160			
158			
			80

Total 854 or 85.4% for the week. 85

The total therefore immediately gives the percentage of his efficiency.

It will thus be seen that the apparatus constitutes means by which inefficient, average, and highly efficient men can be determined, irrespective of their work or the groups of which they form a part. 90

From the foregoing, it is thought that the construction, operation and many advantages of the herein described invention 95 will be apparent to those skilled in the art, without further description, and it will be understood that various changes in the size, shape, proportion, and minor details of construction may be resorted to without departing from the spirit or sacrificing any of the advantages of the invention. 100

Having thus fully described my invention, what I claim as new, and desire to secure by Letters Patent, is:—

105

1. In apparatus for the purpose set forth, the combination with a card having defined spaces for respectively receiving the records of predetermined operations, of a factoring device comprising a body, a transparent sheet over the body having factors thereon for the respective records to be entered on the card, and means interposed between the body and transparent sheet for spacing the two, said spacing means constituting a stop 110 for positioning a card placed beneath the transparent sheet with the different spaces of such card associated with the proper factors thereon on the transparent sheet. 115

2. In apparatus of the character set forth, 120 the combination with a card having defined spaces for respectively receiving the records of predetermined operations, of a factoring device comprising a body, a transparent sheet over the body having factors thereon 125 for the respective records to be entered on the card, and means interposed between the body and sheet forming a pocket having an inner stop wall and in which the card detachably fits and when the latter is in its 130

innermost position therein will have its said spaces associated with the factors for the records to be entered therein.

3. In apparatus for the purpose set forth, 5 a body, a transparent sheet located thereover and having a set of factors thereon, and means for spacing the portion of the sheet carrying the factors from the body a distance sufficient to permit the introduction 10 of a card between the two, said spacing

means constituting a guide for opposite edges of the card and a stop for the inner side of the same.

In testimony whereof, I affix my signature in the presence of two witnesses.

NORMAN BLYTHE BRALY.
